JOHN SELLERS BANCROFT AND AMOS LESLIE KNIGHT, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

MOLD FOR PRINTERS' LEADS AND THE LIKE.

1,355,879.

Specification of Letters Patent. Patented Oct. 19, 1920.

Application filed January 14, 1918. Serial No. 211,880.

To all whom it may concern:

Be it known that we, JOHN SELLERS BANCROFT and AMOS LESLIE KNIGHT, both citizens of the United States, and residents of 5 Philadelphia, county of Philadelphia, State of Pennsylvania, have invented certain new and useful Improvements in Molds for Printers' Leads and the like; and we do hereby declare the following to be a full, 10 clear, and exact description of the same, reference being had to the accompanying drawings, forming a part of this specification, and to the characters of reference marked thereon.

15 This invention relates to mold apparatus for elements of printing forms, particularly to molds of the type disclosed, for example, in United States Letters Patent No. 1,222,415, dated April 10th, 1917. Molds of 20 this type are adapted as part of a type casting machine to produce printers' strip material in the form of rules, leads and like elements of a printing form in fused sections or increments to form strips of in- 25 definite length or in non-fused sections of predetermined length.

The patented apparatus, generally speaking, comprises a mold having an opening for the entrance of molten metal and being 30 open at one end for the exit of the congealed metal means for feeding forwardly the congealed metal and means for forcing molten metal behind the forwardly fed congealed metal. The operations of casting 35 and feeding are carried on in timed relation to each other and are repeated in accordance with the amount of product desired. For feeding the congealed metal a reciprocatory mold blade is shown in the said patent, 40 which blade advances when the metal in the mold cavity is congealed, to push said metal forwardly toward the exit opening of the mold, and retreats thereafter to leave a cavity for the reception of the molten metal 45 to form the succeeding cast.

In casting typemetal strip material having a printing surface, a matrix formed to produce such surface is used, while in the case of non-printing material it is usual to 50 employ a blank matrix.

Molds of this kind for producing printers' strip material are well known commercially and are successful in producing material of the point sizes in ordinary com- 55 mercial use. When material of a lesser

point size is attempted, however, the result is not uniformly satisfactory. In this case the mold cavity frequently has considerable length and a height which is usually either type high or low quad high, but the width 60 or point size dimension of the cavity is relatively very small: consequently, molten metal injected into this cavity has to fill up a space of considerable volume and in doing so it must flow in a condition approaching a film between two ordinarily water-cooled cavity side walls spaced only slightly apart. It will readily be appreciated that these conditions make it difficult to produce satisfactory strip material, particularly that 65 of the fused increment kind; the heat contained in the film of injected molten metal is dissipated more rapidly than desirable. It may here be stated that these molds are commercially used for producing material 70 of point size as low as two points and that the lesser point sizes referred to may be roughly considered as less than two points: but it is to be understood that the scope of 75 the present invention is not intended to be necessarily limited to apparatus for producing material of thickness less than two points.

The object of the present invention is to 80 provide apparatus especially adapted for the production of the lesser point sizes of lead and rule material and the like, particularly 85 apparatus of the general form of the patented apparatus already referred to, this object being accomplished in the preferred 90 manner by the provision of heat retarding means located in proximity to and at the side of the mold cavity. This object will more clearly be set forth and explained in connection with the following description of 95 the embodiment of the invention shown in the accompanying drawings in which—

Figure 1 is a sectional view of a mold of the patented type referred to, the section being substantially in the plane of the mold 100 blade.

Fig. 2 is a cross section of the mold, the section passing through the nozzle opening and also through parts of the pressure screw clamping device.

Fig. 3 is a plan view of the heat dissipation retarding member.

Fig. 4 is an elevation of the rear face of said member, and

Fig. 5 is an elevation of a portion of the 110

rear face of a modified heat retarding member.

Like reference characters in the several figures indicate the same parts.

5 Inasmuch as apparatus substantially corresponding to that of the patent hereinbefore mentioned has gone into extensive public use and is well understood in the art, it is thought to be unnecessary to illustrate 10 herein operating mechanism or stops for the mold blade and means whereby the molten metal is injected into the mold cavity, nor is it necessary, for an understanding of the present improvement, to 15 illustrate in detail means for severing the gate from the side of the strip, especially as operating mechanism and the metal melting and injecting mechanism may substantially correspond to mechanism found in 20 the type casting machines manufactured by the Lanston Monotype Machine Company, which have been in extensive public use for many years.

Referring to the accompanying drawings, 25 it will be seen that the mold illustrated in Figs. 1 and 2 embodies a mold base block 3, which is formed with a channel therethrough in the direction of movement of the mold blade, thus providing front and 30 rear upwardly extending portions 4 which are adapted to be connected across the top of the mold by a tie bar or bars 5. Confined within the channel extending through the mold base are the rear and front type 35 or slide blocks 8 and 9 respectively between which the cavity for the reception of the molten metal is formed, and these type or side blocks are preferably in the form of bars which extend beyond the mold cavity in 40 each direction and are adapted to be separated a distance which will determine the width of the mold cavity and consequently the point size of the element being cast. The front type block is preferably formed 45 in two sections 9 and 10, for convenience of manufacture, inasmuch as it has been found desirable to provide at one side of the mold cavity a channel and exit opening through which air and a portion of the molten metal from the mold cavity may escape 50 in the form of a more or less spongy mass, which, for convenience, may be called a gate lying at one side of the element and adapted to be severed therefrom.

55 By reference to Fig. 2 it will be seen that between the two sections 9 and 10 there is formed a narrow space which widens out within the type block in the form of a channel which is conveniently of a dovetail or triangular cross section, as indicated at 12. The channel 12 and the narrow entrance slot which connects the channel with the mold cavity are preferably 60 slightly tapered or of increasing cross section toward the exit end so as to prevent

binding during the movement of the gate toward the exit of the channel. Where the front type block is made in two sections, as just described, the upper section 9 is preferably made rigid with the lower section 10 70 by being fixed accurately thereto and supported by an upwardly extending portion 10^a of the section 10, to which it is connected by screws or other suitable fastenings, as shown clearly in Fig. 2. 75

The two type blocks forming between them the mold cavity and mold blade channel are positioned laterally of the mold base by packing plate 17 placed back of the rear type block and by the pressure screw 80 18 passing through the front projection 4 of the mold base and adapted to operate against the front type block. This pressure screw, in the preferred construction, is operated periodically in time with the feeding of the element being cast so as to clamp the walls of the mold cavity together during the casting operation and to release such pressure during the feed of the element forwardly in the mold cavity. 90

The bottom of the mold cavity is formed by the mold base and is provided with a nozzle opening 20 through which the molten metal is injected into the mold cavity through a nozzle 20^a indicated in dotted 95 lines in Fig. 1.

The mold illustrated is adapted for the making of material of less than type height, such as leads. The height of the mold cavity is therefore reduced by the use of a blank matrix in the form of a filler blade 57 interposed between the type blocks. This filler blade is conveniently of substantially a thickness corresponding with the point size of the material which the mold is designed to produce, and is provided with overhanging portions 57^a adapted for cooperation with a filler blade support 59, seated upon the type blocks, and against a lateral abutment 23 mounted on the upper 100 face of the rear type block 8: said support being held firmly in position by a matrix clamp 25 having two surfaces 25^a for cooperation with one edge and the top of the matrix or filler blade support and an inclined surface 25^b for cooperation with a corresponding inclined surface on the matrix abutment 23, whereby when the matrix clamp is forced down by its clamping screw 26 the matrix will be forced downwardly and against its abutment where it will be held with precision and in such relation to the type block as to prevent any liability of molten metal escaping through the joints. A squirt preventing shield 40 105 may, if desired, be removably held upon the clamp 25 by the washer 41 yieldingly pressed against the shield by the spring 42 positioned between the washer and the head of the screw 26. 110

The mold blade 27 which is mounted to reciprocate between the side blocks is of a thickness which corresponds to the point size of the material being cast and it is 5 guided by the side blocks, and by the guide extensions 31, 32, the forward and rearward limits of its movement being determined by suitable stops, not shown. The mold blade is provided with means whereby its 10 operating member 35 may be readily attached thereto, such means conveniently and preferably consisting of a centrally located circular bearing into which a journal stud 36 on the end of the member 35 is adapted 15 to work. Immediately forward of this circular bearing the mold blade is formed with an aperture 28^a preferably rectangular for the reception of a lateral rectangular projection formed on the rear end of the 20 gate pusher 28. The projection of the gate pusher fits loosely within the aperture in the mold blade so that the pusher may without binding adapt itself vertically as may be required by the guide channel 12; the parts 25 are rectangular so that in any position a large bearing surface is provided.

The mold above described substantially corresponds with that in commercial use and generally set forth in the patent previously mentioned. To make such mold practically valuable for producing the lesser point sizes of lead and rule material we have provided the member 50 shown particularly in Figs. 3 and 4 and have proportioned the thickness of this member and the type blocks so that the mold cavity is maintained central over the nozzle opening 20. This member 50 consists, as shown, of a liner block having substantially parallel 40 opposite front and rear faces and located, as shown in Fig. 2, between the forward face of the rear type block 8 and the rear face of the blade 27 and of the produced type metal material operated upon by said 45 blade. The length of this element is substantially the same as the length of the rear type block and it is provided with an extension 51 provided with bolt holes 52 for the accommodation of the usual bolts 53 for 50 securing the type blocks together, and with a water cooling port 54 for connecting the water cooling channels 54¹ of the two type blocks: said channels 54¹ being connected and located in the usual manner except that 55 it has been found preferable to eliminate the channel in the upper front block 9, conveniently moving it, as shown, in proximity to the front of the lower front block 10.

The member 50 thus forms by a portion 60 of its front surface a side wall of the mold cavity upon which wall the side of the mold blade slides during its operation: this surface is accordingly smooth. The rear surface of the element is smooth throughout 65 the greater part of its length and such

smooth surface contacts snugly with the front surface of the rear type block against which surface the element abuts and is clamped by the bolts 53; but in proximity to the casting cavity, said rear surface of 70 the element is grooved or otherwise formed to retard conduction of heat from the cavity to the rear type block. Only a limited amount of heat can escape in a given time through the grooved area and consequently 75 the heat of the metal cast in molten, film-like condition in the cavity is retained and prevented from being dissipated through the heat conducting block 8 for a time sufficient to insure the production of a substantially 80 perfect cast filling all portions of the cavity, and of a substantially perfect fusion of this cast to the previous cast in the case of the production by the mold of fused increment material. 85

The heat retarding portion of the element 50 comprises, as illustrated, a series of vertical grooves 55 forming ribs 56 between them; the rear faces of said ribs form the only contacting surfaces of the element 50 90 with the front face of the rear type block 8 in proximity to the casting cavity. Heat from the cavity which passes through the member 50 at this point has therefore a conducting path of reduced area leading to the 95 type block 8 and is thus retarded in its flow. The dissipating heat flow near the base of the material being cast may not in some cases be desired to be retarded because this part of the material is near the hot nozzle, 100 receiving the last portions of the molten metal being injected, and accordingly may be required to be relatively quickly cooled to prevent its being in part sucked back into the injecting mechanism thus leaving a hole 105 in the material at the point of injection. To permit of quick cooling at this point and thus to prevent the formation of imperfect casts, the member 50 may be provided with a plane rear surface 60 in proximity to the bottom of the casting cavity, this surface being produced by stopping the grooves 55 short of the bottom of the member. It will be understood, however, that 110 this heat retarding means formed by that portion of the member 50, the rear surface of which contains the grooves 55 and ribs 56 may be of greater or less extent as may produce the best results. As shown (Fig. 4) the lateral border grooves 55¹ are longer than 115 the grooves 55 so that the heat from the casting which has entered the member 50 is to a greater extent prevented from escaping by flow longitudinally of the member 50 than if the grooves 55¹ were of the same 120 length as the grooves 55; and thus the casting cavity wall formed by the element is maintained hotter.

In the modified member 61 shown in Fig. 5 there are provided both vertical and hori- 130

horizontal grooves so that in this heat retarding portion of the member the conducting paths are the truncated pyramids 62 and the contacting area is merely the sum of the areas of the tops of said truncated pyramids. The grooved portion of the modified structure also extends close to the bottom of the member so that there is left substantially no plane area corresponding with the area 60 of the preferred form shown in Fig. 4. The grooved portion of the modified member is preferably stopped short of the bottom of the member so that there may be no danger of molten metal entering it during injection from the nozzle. It will be seen that horizontal as well as vertical ribs, or both, in any proportion, may be provided in order to control the heat dissipation to the required degree and that the provision of a 20 heat retarding surface of greater or less influence and active area may be accomplished in a variety of ways, it being understood of course that the thickness of the member 50 and the depth of the grooves and the like in its heat retarding portion as well as the area of contact with the rear type block 8 are capable of being varied and proportioned so as to produce the proper degree of heat retardation to fit any particular case. More- 30 over, the retarding member is removable and replaceable by another, so that the one most suitable for any given condition may be selected.

The operation of the apparatus is as usual, the mold blade being reciprocated from a point in advance of the nozzle opening 20 to a point in rear thereof and the metal being injected through the nozzle 20 at the time the blade is in its retracted position. When the cooling and freezing of this cast has taken place the blade moves on its forward reciprocation and pushes the cast ahead of it. The type-metal product is clamped when the blade moves rear- 45 wardly by the screw device 18 and is released by said device when the blade moves forwardly.

We claim:—

1. A mold for strip material elements of printers' forms comprising a mold cavity forming structure including type blocks provided with water cooling channels and heat retarding means in proximity to and at the side of said cavity for retarding the 55 dissipation of heat therefrom.

2. A mold for strip material elements of printers' forms comprising a mold cavity forming structure including type blocks provided with water cooling channels and 60 heat retarding means between said cavity and said channels for retarding the conduction of heat from said cavity to said channels.

3. A mold for strip material elements of

printers' forms comprising blocks, a portion of a face of one of said blocks forming one wall of the mold cavity, a heat retarding member, a portion of a face of which forms another wall of the mold cavity and another face of which is in contact with one 70 of said blocks, the contacting area between said member and said block being reduced to retard the dissipation from said member to said block of heat from the mold cavity.

4. A mold for strip material elements of printers' forms comprising blocks, a portion of a face of one of said blocks forming one wall of the mold cavity, a heat retarding member a portion of a face of which forms another wall of the mold cavity and another 80 face of which is in contact with the other of said blocks, and means between said member and said last-mentioned block and in proximity to the mold cavity for retarding the conduction of heat from said cavity 85 through said member to said last-mentioned block.

5. A mold for strip material elements of printers' forms comprising a member, a portion of the forward face of which forms a 90 wall of the mold cavity, a second member, the forward face of which is in contact with the rearward face of said first member, the area of contact between said members being reduced in proximity to the mold cavity 95 wall of said first member.

6. A heat retarding member for printers' strip material molds comprising a block of heat conducting material provided with a face for forming a mold cavity wall and a 100 second face opposite to and parallel with said first mentioned face, said second face being grooved to reduce its heat conductivity.

7. A mold for strip material elements of printers' forms comprising associated blocks, a heat retarding member contacting with one of said blocks, a portion of the forward face of said member forming one wall of the mold cavity and the rear face thereof in 110 proximity to the mold cavity having a decreased contact area with said block.

8. A fluid-cooled typographic mold embodying the following instrumentalities, to-wit; base and side blocks forming the bottom wall and a side wall of the mold cavity, a second side block, a heat retarding member abutting said second side block and forming a side wall of the mold cavity, a mold blade slidably mounted between said 115 first side block and said member and a matrix forming the top wall of the mold cavity, a portion of the said abutting face of the heat retarding member being grooved to retard heat conductivity between said member and said second side block.

JOHN SELLERS BANCROFT,
AMOS LESLIE KNIGHT,
